J. W. DORSEY.

METHOD AND APPARATUS FOR ELECTRIC LIGHTING AND STARTING VAPOR CONDUCTORS.
APPLICATION FILED JUNE 16, 1917.

1,333,608.

Patented Mar. 16, 1920.

UNITED STATES PATENT OFFICE.

JOHN W. DORSEY, OF WINNIPEG, MANITOBA, CANADA.

METHOD AND APPARATUS FOR ELECTRIC LIGHTING AND STARTING VAPOR CONDUCTORS.

1,333,608.

Specification of Letters Patent. Patented Mar. 16, 1920.

Application filed June 16, 1917. Serial No. 175,165.

To all whom it may concern:

- Be it known that I, JOHN W. DORSEY, a citizen of the United States, residing at Winnipeg, in the Province of Manitoba and 5 Dominion of Canada, have invented new and useful Improvements in Methods and Apparatus for Electric Lighting and Starting Vapor Conductors, of which the following is a specification.
- 10 My invention relates to vapor electric apparatus in which an electric circuit is to be established and maintained through a body of gas or vapor; and has for its principal objects the production of an apparatus which is highly efficient and reliable, which 15 operates without a vacuum, in which the arc vapor does not come in contact with air and is not consumed by oxidation, which may be operated at constant pressure in a heat resisting glass tube, which does not require 20 renewal of electrode material, does not require the use of quartz glass, and in which the glass may be readily replaced. Other objects will more fully appear hereinafter.
- 25 In the usual types of open arcs there is a continual burning away of electrode material which requires that such lamps be regularly "trimmed" for continuous operation. Furthermore, in the usual types of mercury 30 arcs a vacuum is necessary in starting. The purpose of this invention is to eliminate the vacuum and renewal of electrodes, and at the same time maintain a good color of light and high efficiency obtainable from a vapor conductor slightly above atmospheric pressure.
- 35 As illustrative of the invention I will show and describe its embodiment in a lamp of the mercury vapor type, but it will be understood that the invention, for certain 40 features thereof, may be embodied in other forms of apparatus such as lamps employing vapors or gases other than mercury vapor, and other types of apparatus such as current rectifiers, etc. The invention 45 consists, therefore, in the novel apparatus and method for electric lighting and starting vapor conductors, as hereinafter described and claimed, and shown in the accompanying drawings, in which—
- 50 Figure 1 is a front view showing a mercury vapor lamp and mechanism embodying the invention, the operative parts being shown in longitudinal section;
- 55 Fig. 2 is a similar view with the supporting frame and operative solenoids omitted and showing the movable electrode and co-
- operative parts in raised position after the arc has been struck;
- 60 Fig. 3 is a diagram showing the circuit connections.
- 65 Referring to the drawings, A is a casing preferably of heat resisting glass and closed at the lower end which constitutes a receptacle for the liquid electrode B. The casing may be supported in any suitable manner, 70 as by a shell a mounted upon bridge piece a' supported by rods a^2 connected with the base C of the lamp as a whole. The shell a may be provided with any suitable packing material a^3 through which extends the 75 terminal a^4 of tungsten or any suitable metallic conductor sealed into the shell.
- 75 Mounted within the casing is a piston D at the lower end of which is carried a movable electrode E, which latter may be of nickel, tungsten or other suitable material. Both the piston D and the movable electrode are operable by means of rod d at the upper 80 end of which is a fixed stop d' .
- 80 Piston D is preferably composed of iron and asbestos gaskets alternately placed, the iron gaskets d^2 being of greater diameter than the asbestos gaskets d^3 , the piston as a whole fitting within the casing A so as to permit the passage of liquid electrode material and vapor to a point above the piston. The upper portion of the piston is provided 85 with additional gaskets d^4 having beveled upper surfaces for the ready return of the liquid electrode material when the lamp is 90 not in operation.
- 85 Above the piston D is located the starting contact F which is braced from piston rod d by braces f .
- 90 In order to protect casing A adjacent the liquid electrode I provide a sleeve G which is preferably of highly refractory glass or quartz and is movable within the casing. When the piston is in its lowermost position this sleeve may be submerged in the liquid 95 electrode, and when the piston is raised the sleeve may float upon the liquid electrode 100 and surround the lower end of the arc at the point of greatest heat.
- 100 The piston and movable electrode are operated principally by a long pull electromagnet H shown as a double solenoid, the cores h of which are connected to a yoke h' from which extend rods h^2 carrying a second yoke h^3 . Rods h^2 are extended further 105 and carry a heating solenoid I mounted in any suitable structure such as a surrounding

shell provided with plaster and asbestos or other packing. In order to prevent the action of the electro-magnet from being too abrupt a dash-pot K or other suitable device 5 may be provided.

The operation of the lamp will be understood by reference to the diagram of circuit taken in connection with Figs. 1 and 2. Starting with the parts in the positions indicated in Fig. 1, the circuit is closed 10 through wire 1, solenoid I of the heater, wire 2, rod d, movable electrode E, liquid electrode B, and wire 3 to line. The action of heating solenoid I heats the mercury or 15 other liquid electrode B until vaporization takes place. The pressure of the vapor thus generated forces some of the mercury past the piston D, and such of the mercury and vapor as escapes past said piston goes into 20 the casing above the piston where the vapor condenses, and a certain amount of mercury is thus provided above the piston to engage the lower end of rod F, thereby closing the following circuit: wire 1, electro-magnet H, 25 wire 4, winding of relay L, wire 5, rod F, mercury above the piston, rod d, movable electrode E, liquid electrode B and return to line by wire 3. Magnet H is thereby energized and the structure carried by its armature, including yokes h' and h³ starts upward. The first result of this is to move 30 heater I until its lower end is adjacent or above the movable electrode E, and yoke h³ then engages stop d', when the further upward movement carries piston rod d and 35 piston D together with movable electrode E, thus striking the arc. The upward movement continues to the limit, when the parts are in the position shown in Fig. 2. Upon 40 the energization of relay L however, contact F is short circuited by the relay armature through wire 6, so that only the initial current impulse passes alone through contact F.

It will be understood that the magnet H 45 is of low resistance, as also relay L, and consume very little energy, but if desired a holding coil or magnet of less resistance may be provided and arranged to be cut in the circuit after starting as is well known in 50 the art.

During the operation of the lamp the pressure below the piston is slightly greater than atmospheric pressure and serves to maintain a small amount of mercury or other 55 liquid electrode material above the piston to act as a seal for the arc chamber within the casing. Hence it will be seen that while the lamp operates at substantially atmospheric pressure, the pressure is usually slightly 60 above atmospheric pressure. In some instances when starting the pressure of the vaporized liquid electrode below the piston assists the action of the electromagnet in raising the piston, and if the vaporization is 65 sufficiently rapid this action is accentuated.

When the action of the apparatus is to be discontinued, that is, the lamp in this instance extinguished, the current is cut off and the moving parts then have a tendency to return to the positions indicated in Fig. 1. 70 As the mercury vapor below the piston cools, it condenses and the return motion of the parts then takes place. Moreover, as the atmospheric pressure above the piston is no longer counter-balanced by the tension of the 75 mercury vapor below the piston, the mercury which has accumulated and was carried above the piston passes the piston packing and returns to the main body of mercury below the piston, so that the contact with rod 80 F is broken. The parts are then ready to be started again as hereinbefore set forth.

It will be observed in connection with the sleeve G that this sleeve protects the walls of the casing adjacent the lower end of the 85 arc where the heat is the greatest, and thereby avoids bulging and destruction of the casing at this point. The sleeve itself is removable, and if it become injured or opaque it may be readily replaced by a fresh 90 sleeve.

Having described my invention, what I claim as new and desire to secure by Letters Patent of the United States is—

1. Vapor electric apparatus comprising a 95 liquid electrode, a solid electrode, means for starting the vapor arc between said electrodes, and an inclosing casing in which said operation takes place and in which the arc is maintained at a constant pressure greater 100 than atmosphere, all gas or vapor other than that of the liquid electrode being excluded from said casing at the time the arc is formed and during the operation.

2. Vapor electric apparatus comprising a 105 liquid electrode, a solid electrode movable into and out of contact therewith, and a seal of said liquid electrode material above said movable electrode.

3. Vapor electric apparatus comprising 110 a liquid electrode, a solid electrode movable into and out of contact therewith, and a seal of said liquid electrode material located above and movable with said movable electrode.

4. Vapor electric apparatus comprising an inclosing casing, a liquid electrode therein, a solid electrode movable into and out of contact with said liquid electrode, a piston connected with said movable electrode and fitting said casing above said movable electrode, and a seal of said liquid electrode material above said piston. 120

5. Vapor electric apparatus comprising an inclosing casing, the liquid electrode therein, 125 a solid electrode movable into and out of contact with said liquid electrode, a piston connected with said movable electrode and provided with a packing which permits the escape under slight pressure of said liquid 130

electrode material between said piston and casing to a position above said piston, and a seal of said liquid electrode material above said piston.

- 5 6. Vapor electric apparatus comprising an inclosing casing, a liquid electrode therein, a solid electrode movable into and out of contact with said liquid electrode, a piston connected with said movable electrode and fitting said casing above said movable electrode, a seal of said liquid electrode material above said piston, and means heating said liquid electrode to cause the increase of said material above the piston when starting the
- 10 15 action of said apparatus.

7. Vapor electric apparatus comprising an inclosing casing, a liquid electrode therein, a solid electrode movable into and out of contact with said liquid electrode, a piston connected with said movable electrode and fitting said casing above same, and means for heating said liquid electrode to cause the movement of its material past said piston to a point above the same.
- 20 25 8. Vapor electric apparatus comprising an inclosing casing, a liquid electrode therein, a solid electrode movable into and out of contact with said liquid electrode, a rod extending into said casing on which said liquid electrode is carried, a piston mounted on said rod adjacent said movable electrode and fitting the casing, and a seal of said liquid electrode material above said piston.

9. Vapor electric apparatus comprising an inclosing casing, a liquid electrode therein, a solid electrode movable into and out of contact with said liquid electrode, a rod extending into said casing on which said solid electrode is carried, a piston mounted on said rod adjacent said movable electrode and fitting said casing, a seal of said liquid electrode material above said piston, and an electro-magnet for operating said rod.

10. Vapor electric apparatus comprising a liquid electrode, a solid electrode, a movable seal above said solid electrode, and means for moving said solid electrode into and out of contact with said liquid electrode which comprises a long full solenoid magnet and dash pot.

11. Vapor electric apparatus comprising an inclosing casing, a liquid electrode therein, a solid electrode movable into and out of contact with said liquid electrode, a rod extending into said casing on which said electrode is carried, a piston mounted on said rod, adjacent to said movable electrode and fitting said casing, a seal of said liquid electrode material above said piston, means for moving said solid electrode into and out of contact with said liquid electrode which includes a long full solenoid magnet and dash pot.

12. Vapor electric apparatus comprising an inclosing casing, a liquid electrode there-

in, a solid electrode movable into and out of contact with said liquid electrode, a seal of said liquid electrode material above said movable electrode, an electro-magnet for operating said movable electrode, and a contact engaged by said seal material to close the circuit of said electro-magnet.

13. Vapor electric apparatus comprising an inclosing casing, a liquid electrode therein, a solid electrode movable into and out of contact with said liquid electrode, a piston connected with said movable electrode and fitting said casing above the same, a seal of said liquid electrode material above said piston, an electro-magnet for operating said piston and movable electrode, and a contact engaged by said seal material to close the circuit of said electro-magnet.

14. Vapor electric apparatus comprising an inclosing casing, a liquid electrode therein, a solid electrode movable into and out of contact with said liquid electrode, a piston connected with said movable electrode and fitting said casing above same, a seal of said liquid electrode material above said piston, an electro-magnet for operating said piston and movable electrode, a contact in proximity to said material above the piston, and means for heating said liquid electrode to cause the increase of said material above the piston and thereby engagement with said contact to close the circuit of said electro-magnet.

15. Vapor electric apparatus comprising an inclosing casing, a liquid electrode therein, a solid electrode in starting engagement with said liquid electrode, a piston connected with said movable electrode and fitting said casing above the same, a seal of said liquid electrode material above said piston, an electro-magnet for operating said movable electrode, a contact in proximity to said material above the piston and in circuit with said electro-magnet, means for heating said liquid electrode to force some of its material past said piston and thereby increase the amount of said material above said piston to engage said contact and thereby close the circuit of said electro-magnet whereby said electrodes are separated and the vapor arc started.

16. Vapor electric apparatus comprising an inclosing casing, a liquid electrode therein, a solid electrode in starting engagement with said liquid electrode, a piston connected with said movable electrode and fitting said casing above same, a seal of the said liquid electrode material above said piston, an electro-magnet for operating said movable electrode, a contact in proximity to said material above the piston, a heating coil around said liquid electrode, a heating circuit which includes said heating coil, and a circuit in shunt to said heating circuit and including said electro-magnet and said contact.

17. A vapor electric lamp comprising a liquid electrode, a movable solid electrode, means for producing vapor between said electrodes and an inclosing casing of translucent material in which said operation takes place, and in which the arc is started and maintained at a pressure at least as great as atmospheric pressure without the presence of gas or vapor other than that of the liquid electrode.

18. A vapor electric lamp comprising an inclosing casing of translucent material, a liquid electrode therein, a solid electrode movable into and out of contact with said liquid electrode, a piston connected with said movable electrode and fitting the casing above said movable electrode, a liquid seal of said liquid electrode material above said piston, and means for admitting atmospheric pressure to said casing above said seal.

19. In a vapor electric apparatus, comprising a chamber containing a liquid electrode and a movable solid electrode normally in contact, means for causing an initial vapor pressure within said chamber, said means causing a portion of the liquid material to be raised whereby an operating circuit is established for moving said movable electrode.

20. Vapor electric apparatus comprising an inclosing casing, a liquid electrode therein, a piston within said casing, a solid electrode carried by said piston and movable into and out of contact with said liquid electrode, said piston comprising alternately placed metal and mineral fiber gaskets, and a seal of said liquid electrode material above said piston.

21. Vapor electric apparatus comprising an inclosing casing, a vaporizable liquid electrode in the lower portion thereof, a solid electrode movable into and out of contact with said liquid electrode, a piston connected with said movable electrode and fitting said casing above the same, a seal of said liquid electrode mounted above said piston, means for heating said liquid electrode to cause the increase of said material above the piston, and means for causing the upward movement of said movable electrode to strike the arc.

22. Vapor electric apparatus comprising an inclosing casing, a vaporizable liquid electrode in the lower portion thereof, a solid electrode movable into and out of contact with said liquid electrode, a piston connected with said movable electrode and fitting said casing above the same, means for heating said liquid electrode to cause the movement of a portion of the liquid electrode material to pass and accumulate above said piston, and means for causing the upward movement of said movable electrode to strike the arc.

23. Vapor electric apparatus comprising an

inclosing casing, a liquid electrode therein, a solid electrode movable into and out of contact with said liquid electrode, a piston connected with said movable electrode and fitting the casing above the same, a heating solenoid surrounding said liquid electrode, to cause the movement of a portion of its material past said piston to a point above the same, and means for moving said movable electrode out of contact with said liquid electrode to strike the arc and for moving said heating solenoid above the arc location.

24. Vapor electric apparatus comprising an inclosing casing, a liquid electrode therein, a solid electrode movable into and out of contact with said liquid electrode, a piston connected with said movable electrode and fitting the casing above the same, a heating solenoid surrounding said liquid electrode, to cause the movement of a portion of its material past said piston to a point above the same, and means for first moving said heating solenoid from proximity to said liquid electrode and then continuing its movement together with said piston and movable electrode whereby the arc is struck and said casing free to emit light from the arc.

25. Vapor electric apparatus comprising an inclosing casing, a liquid electrode therein, a solid electrode movable into and out of contact with said liquid electrode, a piston connected with said movable electrode and fitting said casing above the same, a seal of said liquid electrode material above said piston, an electro-magnet for operating said piston and movable electrode, a contact in proximity to said material above the piston, means for heating said liquid electrode to cause the increase of said material above the piston and thereby engagement with said contact to close the circuit of said electro-magnet, and a relay for short-circuiting said contact.

26. A vapor electric lamp comprising an inclosing casing of translucent material, a liquid electrode in the lower part of said casing, and a solid electrode structure which includes a solid electrode dipping into said liquid electrode when the lamp is inactive and movable into and out of contact with said liquid electrode, and a sleeve within said casing adjacent said liquid electrode to protect the casing from the heat of the arc, said sleeve being depressed and immersed in the liquid electrode by said solid electrode structure.

27. A vapor electric lamp comprising an inclosing casing of translucent material, a liquid electrode in the lower part of said casing, and a solid electrode structure which includes a solid electrode dipping into said liquid electrode when the lamp is inactive and movable into and out of contact with said liquid electrode, and a sleeve of highly

refractory translucent material within said casing adjacent said liquid electrode to protect the casing from the heat of the arc, said sleeve being depressed and immersed 5 in the liquid electrode by said solid electrode structure.

In testimony whereof I have hereunto set

my hand in presence of two subscribing witnesses.

JOHN W. DORSEY.
